United States Patent Office

Des. 192,227
Patented Feb. 13, 1962

192,227

PLATE HOLDER

Ralph W. Theisen, 7315 N. Ridgeway Ave., Skokie, Ill.

Filed June 5, 1961, Ser. No. 65,446

Term of patent 7 years

(Cl. D44—10)

I claim:

The ornamental design for a plate holder, as shown and described.
